UNITED STATES PATENT OFFICE.

JAMES B. WARDLE, OF TORONTO, ONTARIO, CANADA.

LADDER SCAFFOLD BRACKET.

Application filed May 6, 1927. Serial No. 189,438.

The principal objects of the invention are to devise an improved form of bracket for supporting temporary scaffolds from ladders which will be exceptionally strong and rigid and may be manufactured at very moderate cost.

Further objects are to devise a bracket which may be easily and quickly attached and adjusted to either side of a pair of ladders when said ladders have been set at a proper angle to a wall or structure and which will safely support a planking.

The principal features of the invention consist in the novel construction and arrangement of parts whereby a pivotal platform support is adjustably carried on a rigid frame structure adapted to fit between the side bars of a ladder and which is provided with hook members arranged at the top and bottom adapted to engage the ladder rungs.

In the drawings, Figure 1 is a side elevational view of my improved bracket shown arranged upon a ladder set to a wall, the bracket being supported between the wall and ladder and supporting the scaffold planking.

Figure 2 is a perspective view of the bracket showing the ladder in dotted lines, the bracket being supported on the outer side of the ladder.

Figure 3 is an elevational view of the bracket.

When exterior or interior repair or decorating work is required it is expedient to use a scaffold which may be readily placed in position and moved from place to place and various forms of scaffold brackets have been devised for such use, brackets being placed on two ladders and the scaffold planks being supported therebetween.

The main portion of my improved bracket is formed of two sections 1 and 2, preferably formed of flat steel bars having their upper extremities bent to form the hooks 3 and adapted to embrace a rung 4 of a ladder 5. The lower ends 6 of the bars 1 and 2 are curved inwardly and the extremities thereof are bent laterally to form a pair of lugs 7.

A pair of looped brackets 8 are rigidly secured one to each of the bars 1 and 2 at their upper ends on the side remote from the hooks 3 and a bolt 9 extends through said brackets connecting the upper ends of the bars 1 and 2.

A flat bar 10 bent into U shape and having its ends pivotally supported on the bolt 9 be-

tween the bars 1 and 2 forms the pivotal platform support, the ends of said support being held against the inner edges of the bars 1 and 2 by a pipe spacing member 11 encircling the central portion of the bolt.

The outer or closed end of the pivotal support is bent to form a slotted extension 12 and a flat bar 13 pivotally secured to a bolt 14 secured in the lugs 7 of the bars 1 and 2 extends upwardly into said slot and is adjustably secured by the bolt 15, the bar 13 being provided with a plurality of holes 16.

The bars 1 and 2 are each provided with a plurality of closely arranged holes 17 near the lower end and a pair of flat cross bars 18 and 19 are adjustably secured to the bars 1 and 2 by the bolts 20 extending through the holes 17.

The bar 19 is formed with offset ends 21 which with the ends of the bar 18 form jaws to embrace the bars 1 and 2 and rigidly secured in the inner ends of these jaws are a pair of hook-shaped members 22. These hooks may be adjusted in relation to the upper hooks 3 by shifting the bars 18 and 19 up or down to suit the spacing of the ladder rungs.

It will be seen that the rigid flat frame formed by the bars 1 and 2 rests against the ladder rungs and is held very securely by the two pairs of hook members, consequently the platform support formed by the bar 10 is very rigid and presents a two point support for the planking 23 which is placed thereon.

The upper end of the bar 13 extends above the outer end of the support bar 10 and ensures the platform planking from slipping off the bracket.

Under some working conditions it is desirable for the workmen to operate on the inside of the ladders and the brackets are hung on the inside of the ladders as shown in Figure 1, or they may arrange the brackets on the outer side of the ladders as shown in Figure 2. In some cases it may be desirable to use a wide scaffold and brackets may then be arranged on each ladder on both inner and outer sides to support a scaffold on both sides of the ladders, permitting a work impossible to be finished from the inside owing to the angular relation of the ladders to the wall to be finished from the outside without the necessity of changing the one inside bracket to the outside.

A single ladder may be used in many cases

to advantage by a workman by placing a short board on the forked member for a rest instead of using a rung of the ladder.

What I claim as my invention is:

- 5 1. A ladder scaffold bracket, comprising a rigid flat U-shaped frame, the leg portions of which are spaced parallelly apart and are adapted to rest against the ladder rungs adjacent their outer ends, the ends of said leg portions being curved downwardly to form a pair of hooks to encircle the outer ends of a ladder rung, a pair of hooks adjustably secured to said frame adjacent to its lower end and immediately adjacent the inward side 15 of said leg portions, a U-shaped platform support pivoted at the sides of the frame at its upper end, and a strut pivoted at the lower end of the frame and adjustably connected to the arched outer end of the U-shaped plat- 20 form support.
2. A ladder scaffold bracket, comprising a rigid flat frame having side members spaced apart adapted to rest against the outer ends of the ladder rungs and having a pair of 25 hooks at the top, a cross bar extending between and adjustably secured to the side members of said frame, a pair of hooks rigidly secured to said cross bar, immediately adjacent the inward side of said side members, a strut pivotally secured to the bottom of said frame, and a U-shaped platform support pivotally secured to the top of the side members of said frame and adjustably connected at its outer arched end to said strut.

3. A ladder scaffold bracket, comprising 35 a pair of flat bars hooked at the upper ends and having inwardly curved lower ends terminating in laterally bent lugs, a cross bolt connecting the upper ends of said bars, an adjustable cross bar secured between the 40 lower ends of said hooked bars, hooks secured to said cross bar, a strut pivoted between said lugs, a U-shaped bar having its ends pivoted on said bolt, and means for adjustably connecting the outer end of said U-shaped bar 45 with said strut.

4. A ladder scaffold bracket, comprising a rigid flat frame having side members spaced apart adapted to rest against the outer ends of the ladder rungs and having a pair of 50 hooks at the top, said side members having a plurality of oppositely arranged holes adjacent the lower end, a cross bar extending between said side members and having holes 55 in the outer ends to register with the holes in the side members, bolts extending through the registering holes and clamping said cross bar in an adjusted position on the side members, a pair of hooks extending from said cross bar immediately adjacent the inner side 60 of said side members adapted to engage a ladder rung, a strut pivotally secured to the bottom of said frame, and a platform support pivotally secured to the top of the side members of the frame and adjustably connected at its other end to said strut. 65

JAMES B. WARDLE.
